UNITED STATES PATENT OFFICE.

HATHERLY SPEAR, OF PORTLAND, MAINE.

IMPROVEMENT IN PUMPS.

Specification forming part of Letters Patent No. 121,209, dated November 21, 1871.

To all whom it may concern:

Be it known that I, HATHERLY SPEAR, of Portland, in the county of Cumberland and State of Maine, have invented an Improved Pump; and I do hereby declare the following to be a full, clear, and exact description of the same, reference being had to the accompanying drawing forming part of this specification, in which—

Figure 1 is a side elevation, the air-pump being shown in section. Figs. 2 and 3 represent the construction of the cocks G G', and Fig. 4 represents a vertical section of the pump.

Similar letters of reference in the accompanying drawing indicate corresponding parts.

This invention relates more particularly to that class of pumps which is used for very deep wells or for mining purposes, where the water is to be raised more than thirty-three feet; and it consists in the employment of a system of relays, by which the water can be raised to any height by atmospheric pressure, and in the details of construction herein set forth.

In the drawing, A B C B¹ C¹, &c., represent a series of hollow castings forming the chamber of the pump, connected by pipes P P¹ P² P³ P⁴, &c., according to the number of relays employed, and provided with one or more strainers, s s, arranged in any suitable manner. The chambers B B¹ B², &c., are each provided with a ball-valve, b b¹, &c., which seats downward, as shown in Fig. 4, while the chambers C C¹ C², &c., are connected in pairs by means of a bent pipe, D, and are each provided with an elastic tubular diaphragm, f, inserted through the collar at the extremity of the chamber, and attached at the ends to the casting by means of the screw connection that unites the casting and the pipe, or in any other preferable manner. The pipe D is connected, by a branch or branches, d, to an air-exhaust, E, worked by an engine, not shown in the drawing. The exhaust may be of any form of construction that the proprietor may prefer to use. The pipe D that connects two chambers, C C¹, is provided with a pair of three-way cocks, G G', each having one passage leading to the exhaust, another leading to the chamber C, and a third leading to the open air; said cocks being connected by a rod or chains, H, and operated from the engine or other motive power in such a manner that when any one of the passages in one cock is closed the corresponding passage in the other is open. The uppermost

chamber C¹ is necessarily constructed somewhat differently from the other of the series, being provided with a discharge-nozzle, I, and with a float valve, v, which, when the water fills the chamber, closes the mouth of the tube D and prevents the escape of the water into the exhaust. The chamber is, of course, covered, as shown at c, and the discharge-nozzle is provided with a valve, v', which readily opens to discharge the water, and closes automatically to prevent the ingress of air, while the exhaust is in communication with the chamber. In the drawing I have shown but one chamber, provided with the diaphragm f. The number of these chambers, however, depend upon the length of the pump and the number or relays thereby rendered necessary. They are to be arranged alternately with the valve-chamber, and placed from fifteen to thirty feet apart, according to the size and power of the exhausting apparatus, and the degree to which a vacuum can be approximated in the chamber. The whole apparatus may be suspended or supported in the well by chains J J', if preferred.

The operation of this improved pump is as follows: The first movement of the machinery connected with the exhaust and the cocks, as described, closes the upper cock G¹, opens the lower one, and operates the exhaust. The air is exhausted from the pipe D and the chamber C. The valve b¹ closes while the valve b opens, and the water rushing up to fill the vacuum enters and fills the diaphragm f, and expands it till it fills the whole chamber C. All this is the work of an instant, and at the next moment the action of the machinery reverses the position of the cocks G G', opening way D through the upper one, closing the way D at the lower one, and opening the communication through the cock G from the chamber C to the open air. Simultaneously therewith the exhaust again operates, but this time it pumps the air from chamber C¹ and from the small valve-chamber B¹ below it, allowing the atmospheric pressure that is communicated through the cock G to squeeze the diaphragm f in chamber C, and force all the water contained within it up into the chamber C¹. The next movement of the machinery reverses the cocks again and exhausts from chamber C, as in the first place, and so on as long as the pump is in operation. It will be borne in mind that the diaphragm-chambers are divided into two sets.

C C² C⁴ C⁶, &c., constituting one set, and C¹ C³ C⁵, &c., constituting the other, and that one entire set is exhausted simultaneously at one moment and the other entire set at the next moment. The upper chamber C^x need not be provided with a diaphragm, as the water is not to be forced above it, but simply to be discharged at the valve v'.

In the matter of construction the details shown and described herein may be considerably varied without departing from the spirit of my invention. In fact, a pump constructed for practical operation would be dissimilar to the one shown in the drawing in several respects. In the first place the chamber C C¹, &c., would be considerably larger than shown in proportion to the valve-chambers B B¹, &c., so as to get room for the expansion of the diaphragms and enable more water to be thrown. Again, a large number of chambers would be employed, connected by pipes P P¹, &c., each from twelve to twenty-five feet long, according to the power and capacity of the exhaust. The form of the chamber and the precise method of operating the valves, &c., that is here shown are not, of course, essential, but may be modified according to circumstances. The inner wall of the chamber C C¹, &c., may be channeled, grooved, or corrugated, so as to provide passages leading from the air-duct all around the chamber, in order that when the diaphragm is filled out and presses against the wall on every side the air may be still able to pass in all around it, and the atmospheric pressure be equally applied to it in every direction.

The diaphragm may be made of any suitable material, and fastened in place in any suitable

manner. A straight elastic tube, f, connected to the screw-joint at either end, is, however, believed to be the most convenient for adjustment, removal, &c. Any kind of valve may be substituted for the ball-valve, and instead of employing enlarged valve-chambers B B¹ the valves might be placed in the pipes P P¹, if preferred. I regard the valve-chambers B B¹, &c., as simply enlargements of the pipes for the accommodation of the valves. The chambers may be arranged in a vertical line, as shown, or at any inclination that may be convenient.

Having thus described my invention, what I claim as new therein, and desire to secure by Letters Patent, is—

1. A system of chambers C C^x, separated by valves b¹ b², and all except the upper one containing an elastic diaphragm, f, when combined with an exhaust and with connecting-pipes D and cocks G G¹, operating as herein described.

2. The atmospheric relay-pump herein described, consisting essentially of the base A, the chambers C C^x, the valve-chambers B B¹, the diaphragms f f, the valves b b¹, the pipes D D, the cocks G G¹, the exhaust E, the pipes P P¹, the outlet I, and the valves v v', all combined and operating substantially as and for the purposes herein set forth.

3. The tubular diaphragms f, in combination with the chambers C C¹, when arranged in the manner and for the purpose specified.

HATHERLY SPEAR.
